UNITED STATES PATENT OFFICE

1,937,754

TELEPHONY

Marion W. Gieskieng, Denver, Colo., assignor, by direct and mesne assignments, to Radio Corporation of America, New York, N. Y., a corporation

Application November 18, 1929
Serial No. 407,974

5 Claims. (Cl. 178—44)

This invention relates to an improved method and apparatus for transmitting sound and has reference more particularly to means for reducing static and other line interferences in connection with reproducing apparatus employing a vibrating beam of light and a photo-electric cell.

In that class of apparatus to which my invention relates, means is provided whereby vibrations are imparted to a beam of ordinary light or to a beam of cathode rays, which correspond to the vibrations of the sound waves, which it is desired to transmit. The beam is directed towards a photo-electric cell from which it is separated by a shield having an aperture or slot through which the light must pass before it can enter the photo-electric cell. The cell is connected to the grid circuit of a vacuum tube amplifier in the plate circuit of which a telephone or other receiver is connected.

When sound waves are transmitted to a distance by wires or by wireless apparatus and then reproduced as audible sound by means of a telephone or loud speaker apparatus, it is found that static and other line interferences effect the reproduction adversely and at times the static disturbances are so great that they make the speech or other signal waves unintelligible.

The efficiency of a radio transmitter can be greatly increased without losing overtones, by the trimming of modulation peaks and my apparatus is especially adapted for this purpose.

By use of my apparatus it is possible to protect radio reception devices from surges, modulation peaks and above all from atmospheric static to such an extent that the loudest crash of static will be no louder than the loudest signal received, and it therefore makes it possible to receive weak signals and to limit the static to approximately the same level as the weak signals.

The above desirable results are attained by the simple expedient of forming the opening or window in the shield that is interposed between the source of light and the photo-electric cell in a way that will be hereinafter described and to employ in combination with such a shield a narrow beam of light that is wider than the widest portion of the window.

It is well understood that the amount of current that will pass through a photo-electric cell is directly proportional to the amount of light that is permitted to enter the cell or to the intensity of the illumination. For the purpose of varying the illumination within the photo-electric cells of photo-electric wave transmitting cir-

cuits the shield is provided with a slot or opening which lies in the path of a beam of light that is reflected from a mirror that is vibrated in accordance with the sound vibrations that are to be transmitted; this beam is partially intercepted by the shield or screen and that portion of the beam that overlaps the window enters the photo-electric cell causing a varying area of the cathode surface within the cell to be illuminated with the result that slight changes are produced in currents flowing through the cell which correspond strictly to the vibrations of the light beam, and these variations are then amplified by well known means.

It is evident that with an apparatus like that shown and described in U. S. Letters Patent No. 1,527,649, the variations in the current that passes through the photo-electric cell will always be directly proportional to the amplitude of the vibrations of the light beam and therefore atmospheric static will cause loud crashing sounds that drown out the other signals with the result that the sound produced by the receiving apparatus will vary greatly from that which is being transmitted.

I have found that if the light beam employed is narrow in the direction in which it vibrates and wider than the window in the screen and if the window is of such shape that the width of the opening therein is different at different points along its length, greatly improved reception can be obtained. By this simple expedient it is also possible to produce a variety of different effects that are of great importance in this art and which will hereinafter be called attention to.

In order to describe my invention in such a way that it can readily be understood and so that anyone skilled in this art can practice the same, reference will now be had to the accompanying drawings on which the invention has been illustrated and in which:

Fig. 1 shows diagrammatically a two-way telephone system embodying my invention;

Fig. 2 shows a slightly modified system in which a beam of cathode rays is vibrated by an electromagnet;

Fig. 3 is a view showing the relationship of the light, the mirror, the photo-electro cell and the screen;

Fig. 4 is a view of a screen showing one form of opening;

Fig. 5 is a diagram showing the relationship of the curves of the opening in the screen at the transmitting end and the receiving end of the circuit;

Fig. 6 is a view similar to Fig. 4 and shows a modified form of opening;

Fig. 7 shows a screen having an opening designed for secret transmission; and

5 Fig. 8 shows another form of opening.

In the drawings the transmitter 10 is provided with a diaphragm 11 which is vibrated by the action of the sound waves. A mirror 12 is mounted for oscillation about a pivot 13 and is connected with the diaphragm by means of a thin rod 14 which transmits motion from the diaphragm to the mirror. A lamp 15 is located a short distance from the mirror and is preferably separated from the latter by a screen 16 that has a narrow slot through which the light may pass to the mirror. Located in the path of the reflected beam is a screen or shield 17, which is provided with a window, or opening 18 that has a peculiar shape and through which the light must pass in order to enter the photo-electric cell 19. The photo-electric cell is of the usual construction and comprises a sealed tube having a central anode 20 and a cathode 21, which consists of a coating of silver which has been formed on the wall of the tube and upon which has been deposited metallic potassium. Before finally sealing, the tube is subjected to a Geissler discharge in an atmosphere of hydrogen. An opening 22 is left in the cathode to provide a window for the passage of light which falls upon the interior surface of the cathode.

When this cell is placed in series with a suitable source of potential, the current therethrough is dependent upon the quantity of light entering the cell or the area of cathode illuminated. The exact form of photo-electric cell is immaterial and any form can be used. The term "photo-electric cell" or "photo-electric device" is intended to apply to any means which has the property of changing the current passing therethrough in response to any change in the quantity or area of illumination to which the cell is subjected, regardless of the rate at which the changes in illumination occur.

45 In operation, the beam of light 23, oscillates in accordance with the vibrations that are imparted to the mirror 12, either by the diaphragm 11 or by the armature 24 of the galvanometer 25. The transmitter 10 is used at the transmitting end 50 of the line and the galvanometer 25 at the receiving end of the line. The amount of light that enters the photo-electric cell depends on the position of the beam of light with respect to the opening 18 as this is so constructed that its width varies in a manner that will hereafter be described. It is apparent from Fig. 3 that if the beam moves in the direction of arrow a , it will move from a narrow to a wider part of the opening and therefore the amount of light that enters the photo-electric cell will increase, whereas, when it moves in the opposite direction, the amount will decrease. The rate of increase and of decrease will be controlled jointly by the rate of vibration of the beam and the rate at which the width of the beam opening increases or decreases at the particular point where the beam is located.

70 The variation in the illumination of the photo-electric cell will cause variations in the current that flows through the cell. The circuit through the cell 19 includes a battery 26 and a noninductive resistance 27, this circuit being in electric connection with the grid or control circuit of the thermionic tube 28 from a point 29 intermediate the resistance 27 and the anode 20. The 75 filament 30 is connected to the opposite end of

the resistance, preferably through a few battery cells 31 to maintain the proper difference of potential between the filament and the grid. The plate circuit is supplied from a battery 32 and included in the plate circuit are the transmission lines 33 and 34 across which are connected the receivers or the loud speaking reproducing devices 36 shown in Fig. 1.

With the parts assembled as shown in Fig. 1, let us assume that a sound is produced at S adjacent to the transmitter 10. This will cause the diaphragm 11 to vibrate and this in turn will vibrate the mirror 12 about its pivot 13 and this will cause the beam 23 to vibrate and to move back and forth over the screen 17 and the window 18 whereupon the illumination in the cell will be varied and this will set up a variable current through the photo-electric cell which will be amplified and flow through the primary coil of transformer 37 and thereby setting up a corresponding current in lines 33 and 34. A galvanometer 25 is connected with line 34 through a potentiometer 37 and therefore the mirror 12a will be vibrated and cause the beam of light to move over the opening in screen 17 whereupon a current will be set up in the loud speaker circuit 36 and this will operate the loud speaker or the headset 39. There is a difference between the openings 18 in the screen at the transmitter and at the receiver and this has been illustrated in Figs. 4 and 6 in which the full line represents the outline of the opening in the former and the dotted line the shape of the opening in the latter while OB represents a line with respect to which the full line and the dotted line curves 90 are symmetrical or nearly so. In order to explain the theory of the operation, reference will be had to Fig. 5 in which the straight line OB corresponds to the lines so indicated in Figs. 4 and 6 and which will be considered as being the 95 upper edge of the opening through which light passes. If the ordinate OY represents the amount of light that is admitted to the photo-electric cell at the transmitting end and the abscissa OX the quantity of light that is admitted to the photo-electric device at the receiving end we will find that if line OB makes a 45 degree angle with the abscissa that the input and output will be the same and therefore Oa equals ob. The static and other line disturbances are 100 not generated in the transmission device but are "picked up" on the line between the sending and the receiving stations and are sometimes of greater intensity than the signal currents. If the openings in the two screens had straight relatively inclined sides, the static and other foreign currents would produce sounds that had the same relation to the signal sounds as the relative values of the currents and the static disturbances and line noises would therefore drown out the signals.

105 It is the object of this invention to produce an apparatus in which the signal currents will first be amplified and then sent over the line or over the air in magnified form and when they reach the reproducing apparatus to reduce them to the same extent as the magnification whereby they will produce the same effect as if they had been transmitted by an ordinary apparatus. The static and other line disturbances which come onto the line between the two stations are not 110 amplified, but are subjected to the same reducing effect as the signal currents whereby the static and other undesirable currents are greatly reduced while the signal currents are first amplified and then reduced. Since the intensity of 115

the sounds reproduced depend on the amount of light that enters the photo-electric cell at the receiving station and since this is determined by the width of the opening 18, it is evident that 5 the value of any static disturbance can be strictly limited by decreasing the taper of the opening towards its ends as it is obvious that if the sides of the opening are parallel no sound will be produced as there will be no variation in the amount 10 of light that enters the photo-electric cell regardless of the amplitude of the vibration of the light beam.

Referring now to Fig. 5, let us assume that a beam of light is projected onto the screen 17 at 15 the sending station and that an amount equal to five units would enter the cell when the beam was in the position indicated by line *b*—*e* if the edge of the opening were along a straight inclined line *OB*. Since the opening is curved as 20 indicated by the solid line 12 units of light will enter the cell instead of 5 and this will be equivalent, in effect, to light of the value of *Od* entering the opening at *f* if the edge of the opening were straight as indicated by line *OB*, the effect 25 on the action of the photo-electric cell will therefore be the same as if the beam had been swung to *g*—*h*. In order to reduce the effect at the receiving station, the opening has its corresponding side reversely curved as indicated by the dotted line and the beam of light will strike the curve of the opening at the receiving end at *h* 30 which permits 5 units of light to enter. Let us now suppose that static to a value equivalent to five units of light is picked up by the circuit. 35 Since this is not amplified, it will be effective to move the light beam to *eb* which will produce an effect equivalent to a single unit (*Oi*). From the example given, it will be seen that the signal will be reproduced at its original value, but 40 static and line disturbances will be greatly diminished by properly shaping the openings in the screens 17.

In Fig. 4, line *OB* has been inclined thirty degrees, instead, forty-five, as in Fig. 5, but the 45 operation is the same. In Fig. 6 both sides of the opening are curved but the variation per unit of length is the same as in Fig. 4 and therefore the effect is the same.

If secret signals are to be sent, the screen at 50 the sending station may be provided with several indentations along its edge or edges like those shown in full lines in Fig. 7, and the screen at the receiving station having reversed indentations somewhat as shown by dotted lines. These 55 screens are provided in sets which are properly coordinated and when used as described, the one at the sending end will effectively scramble the signal and the one at the receiving end "unscramble" the same so that it will be intelligible.

In Fig. 2 I have shown an apparatus in which 60 a beam of cathode rays is employed in the place of the light beam. Cathode rays can be influenced by an electromagnet and therefore instead of using a galvanometer an electromagnet 40 is arranged adjacent the beam and subjected to a variable current produced by a telephone transmitter or which may be obtained from the lines 33 and 34. The beam 41 will be vibrated over a shield 17 that is formed from material opaque 65 to the cathode rays and which has an opening 18 like that already described.

Instead of a loud speaker or a telephone receiver a suitable automatic recorder may be used when the device is employed for telegraphy.

75 By using a screen like that shown in Fig. 8, a

multiplication of the frequency can be obtained. It is desirable to so adjust the parts that the light beam will vibrate equally on opposite sides of the line *OY* because at this point the maximum magnification of the signal currents is obtained as well as the maximum reduction of the static disturbance and therefore within a range that can be designated the "noise band" the objectionable currents will be quite effectively eliminated.

If we consider that those portions of the opening that have been designated by *X* in Fig. 4 are the ones employed for signals of the usual intensity, then those portions of the curved sides beyond this area can be of smaller inclination with respect to the direction of travel of the light beam and therefore the variations in the illumination of the photo-electric cell will be comparatively small for the light beam travel beyond this portion of the curve.

Where radio frequencies are used, the cathode ray beam is preferably, as when this is employed there are no moving parts that have inertia and therefore the beam can be vibrated at any frequency within the capacity of the electromagnet, 100 and the photo-electric device.

The limiting properties of the window 18 may be so designed that static or other interferences or cross talk can be held within any desired levels when used with telegraphy, telephony, facsimile, 105 television, etc. This device when properly connected and adjusted will hold all peaks or surges within the operating limits of the transmitter due to the absolute limiting and smoothing feature of window 18. This device or limiter can be used 110 in series to alter to a finer degree the response to certain energy levels. Frequency multiplication can readily be obtained by properly designing the window.

It is also possible to obtain somewhat similar 115 results by magnetic means but since this is a different invention, it will not be described herein.

It is evident that it is the relative movement between the window and the beam that produces the result desired and it is therefore possible to 120 move the screen 17 instead of the light beam, but such reversal is obviously useful only where slow variations are sufficient for the purpose under consideration. Since cathode rays can be used as well as light rays the term "light beam" should 125 be construed as covering both.

Although the screen 17 has been described as provided with an opening 18, it is evident that it may be made of glass or other material that is transparent to the rays used and have portions 130 covered with an opaque substance or any other equivalent means may be substituted. A suitable metal screen is believed to be the most desirable but glass may be used and even metal when used with cathode rays.

Having described the invention what is claimed as new is:

1. A method of reducing interference in transmission systems which consists in vibrating a beam of light in accordance with sound waves, 140 projecting said vibrating beam upon a light sensitive element to transform said vibrations into current variations, controlling the projection to produce distorted current variations, amplifying the distorted current variations, transmitting the amplified variations through an interference region, collecting transmitted distorted variations and interference currents, and treating the combined distorted variations and interference currents so that the distorted va- 150

- riations are de-distorted to conform with the original sound waves and the interference is limited to substantially the same level as the weak components of the sound waves.
5. 2. A method of reducing interference in transmission systems which consists in vibrating a beam of light in accordance with sound waves projecting said vibrating beam upon a light sensitive element to transform said vibrations into current variations, controlling the projection to produce distorted current variations, amplifying the distorted current variations, transmitting the amplified variations through an interference region, collecting transmitted distorted variations and interference currents, and converting the combined distorted variations and interference currents to light vibrations, and transforming the latter to current variations in a manner such that the distorted variations are de-distorted to conform with the original sound waves and the interference is limited to substantially the same level as the weak components of the sound waves.
3. A method of reducing interference in transmission systems which consists in vibrating a beam of light in accordance with sound waves projecting said vibrating beam upon a light sensitive element to transform said vibrations into current variations, controlling the projection to produce distorted current variations, amplifying the distorted current variations, transmitting the amplified variations through an interference region, collecting transmitted distorted variations and interference currents, and converting the combined distorted variations and interference currents to light vibrations, and transforming the latter to current variations in a manner inverse to the original distortion step so that the distorted variations are de-distorted to conform with the original sound waves and the interference is limited to substantially the same level as the weak components of the sound waves.
4. A communication system comprising a transmission station including means for converting sound waves into light vibrations, means to convert light vibrations into current variations, means to amplify the latter, and means for controlling the light vibration conversion in a predetermined manner so that current variations are produced distorted with respect to the sound waves, a transmission medium responsive to interference currents, a receiving station including means for collecting distorted current variations and interference currents transmitted through said medium, means for converting the combined variations and interference currents to light vibrations, means for transforming the latter into current variations, and means for controlling the transformation so that the distorted variations are de-distorted to conform with the original sound waves and the interference limited to at least the same level as the weak components of the sound waves.
5. A communication system comprising a transmission station including means for converting sound waves into light vibrations, means to convert light vibrations into current variations, means to amplify the latter, and means for controlling the light vibration conversion in a predetermined manner so that current variations are produced distorted with respect to the sound waves, a transmission medium responsive to interference currents, a receiving station including means for collecting distorted current variations and interference currents transmitted through said medium, means for converting the combined variations and interference currents to light vibrations, means for transforming the latter into current variations, and means for effecting the transformation in a manner inverse to said transmitter distortion so that the distorted variations are de-distorted to conform with the original sound waves and the interference limited to at least the same level as the weak components of the sound waves.
